Primary Examiner — Mimosa De(74) *Attorney, Agent, or Firm* — Wood Herron & Evans LLP(57) **CLAIM**

The ornamental design for a dynamic front seat, as shown and described.

DESCRIPTION

FIG. 1 is a front quarter right side view of a dynamic front seat according to a first embodiment of the present invention.

FIG. 2 is a rear quarter left side view of the dynamic front seat shown in FIG. 1.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a front quarter right side view of an alternative embodiment of the dynamic front seat of the present invention.

FIG. 9 is a rear quarter left side view thereof.

FIG. 10 is a right side view thereof; and,

FIG. 11 is a left side view thereof.

Any elements shown in broken lines form no part of the claimed invention, but are instead included to show environmental aspects thereof. The broken lines adjacent to the shaded portion form an unclaimed boundary of the design.
